DESIGN FOR A GAME BOARD

Vincent Linfante, Brooklyn, N. Y.

Application March 16, 1936, Serial No. 61,659

Term of patent 14 years

To all whom it may concern:

Be it known that I, Vincent Linfante, a citizen of the United States, residing at Brooklyn, in the county of Kings and State of New York, have invented a new, original, and ornamental Design for Game Boards, of which the following is a specification, reference being had to the accompanying drawing, forming part thereof.

Fig. 1 is a plan view and Fig. 2 is an edge view, partly in section of a game board, showing my new design.

I claim:

The ornamental design for a game board, as shown.

VINCENT LINFANTE.
